(57) **CLAIM**

The ornamental design for a foldable ramped footstool, substantially as shown and described.

DESCRIPTION

FIG. 1 is a front elevational view of a foldable ramped footstool;

FIG. 2 is a rear elevational view of the foldable ramped footstool;

FIG. 3 is a top elevational view of the foldable ramped footstool;

FIG. 4 is a bottom elevational view of the foldable ramped footstool with the legs folded flat;

FIG. 5 is a front perspective view of the foldable ramped footstool;

FIG. 6 is a right side elevational view of the foldable ramped footstool;

FIG. 7 is a top elevational view of the foldable ramped footstool with the legs folded flat;

FIG. 8 is a top elevational view of the foldable ramped footstool with the legs folded flat and with inner hinges unlocked;

FIG. 9 is a bottom elevational view of the foldable ramped footstool in a completely folded position;

FIG. 10 is a top elevational view of the foldable ramped footstool in a completely folded position; and,

FIG. 11 is a bottom elevational view of the foldable ramped footstool in an open position.

A left side elevational view is not shown because it is symmetric to the right side elevational view.

The broken lines in the drawings depict environmental subject matter, specifically a massager unit and hinges, and form no part of the claimed design.
